UNITED STATES PATENT OFFICE.

MAX C. MILLER, OF CUMBERLAND HILL, RHODE ISLAND, ASSIGNOR TO JENCKES KNITTING MACHINE COMPANY, OF PAWTUCKET, RHODE ISLAND, A CORPORATION OF RHODE ISLAND.

FABRIC RECEIVER FOR KNITTING MACHINES.

Original application filed April 5, 1921, Serial No. 458,640. Divided and this application filed May 27, 1922. Serial No. 564,210.

To all whom it may concern:

Be it known that I, MAX C. MILLER, a citizen of Germany, residing at Cumberland Hill, in the county of Cumberland and State of Rhode Island, have invented certain new and useful Improvements in Fabric Receivers for Knitting Machines; and I do hereby declare the following to be a full, clear, and exact description of the invention, such as will enable others skilled in the art to which it appertains to make and use the same.

The invention relates to that class of seamless hosiery knitting machines in which the needle cylinder is given a rotary movement in knitting the leg and foot and is given a reciprocatory movement in knitting the heel and toe of a stocking.

Machines of the above type are usually provided with fabric receivers for receiving the web of fabric which passes down through the interior of the needle cylinder during the knitting.

It is the object of the present invention to provide novel and improved mechanism for rotating the fabric receiver in unison with the needle cylinder during rotary knitting and for dis-continuing its movement during reciprocatory knitting which is simple in construction, avoids strain and wear on the gearing through which the needle cylinder is rotated, and permits access to the receiver at all times without danger of injury to the operator. To these ends the invention comprises the features of construction and combination of parts hereinafter described and referred to in the claims.

The present application is a division of application Serial No. 458,640, filed April 5, 1921, and in the drawings a preferred form of the invention is shown applied to the machine which is fully shown and described in said application. Fig. 1 is a side elevation partly in section showing so much of the machine as is necessary to illustrate the application of the present invention thereto, and Fig. 2 is a detail of the means for connecting and disconnecting the fabric receiver and its actuating mechanism.

The machine shown in the drawings is provided with a rotary needle cylinder in-

dicated at 2 which is rotated and reciprocated through a gear 4 connected with its lower end and engaged by a similar gear 6 secured to the upper end of a vertical shaft 8. The lower end of the shaft carries a beveled gear 10 engaged and driven from a similar gear 12 loosely mounted on the driving shaft 14. The motion changing mechanism for rotating and oscillating the needle cylinder comprises two pinions indicated at 16, one of which is secured to the shaft, and the other of which is mounted to oscillate about the shaft, and a clutch arranged between the pinions and adapted to be shifted by the pattern mechanism of the machine to connect either one or the other of the pinions with the gear 12 through which the needle cylinder is driven. The oscillating pinion is actuated through a segment lever 18 mounted on a work shaft 20 and oscillated from a crank 22 which is carried by a gear 24 and is connected to the lever through a link 26. The gear is engaged and continuously driven by the pinion 16 which is fixed to the driving shaft.

In the form shown the fabric receiver consists of a can 28, the upper end of which is open to receive the knitting fabric which passes down through the interior of the needle cylinder during the knitting. The upper end of the can is arranged at some distance below the lower end of the needle cylinder and the supports therefor and the actuating mechanism for the can is connected therewith below its upper end so that there may be a free unobstructed space at the upper end of the can permitting free access thereto at all times without danger of injury to the operator. For simplicity and for convenience in removing and replacing the can the actuating mechanism therefor is preferably located at its lower end. As shown the can 28 is mounted upon the upper end of a vertical shaft 30 which is rotated in unison with the needle cylinder through a train of gearing which is separate and independent of the train of gearing through which rotary motion is transmitted to the needle cylinder. This gearing comprises a beveled gear 32 on the lower end of the shaft which engages a similar gear 34 on

one end of a shaft 36, the other end of which is connected by beveled gears 38 with the lower end of a vertical shaft 40. The upper end of the shaft 40 is provided with a beveled gear 42 which is engaged and driven by a beveled gear 44 carried by the continuously rotating crank gear 24. The gearing is so proportioned that the shaft 30 rotates in unison with the needle cylinder making one revolution for each revolution of the needle cylinder.

The lower end of the can is connected with the shaft 30 by a clutch, one member of which consists of an annular rib 46 formed on the lower end of the can, and provided with clutch teeth on its lower edge, and the other member of which comprises a horizontal disk 48 secured to the shaft and provided with teeth engaged by the teeth on the rib 46. During rotary knitting the rib 46 rests on the disk 48 so that the can rotates with the shaft 30 in unison with the needle cylinder. When the motion of the needle cylinder is changed from rotary to reciprocating the clutch members 46 and 48 are disengaged, thus disconnecting the can from the shaft 30 so that it will remain stationary during the reciprocation of the needle cylinder. Upon the change back to rotary motion the clutch members are re-engaged to re-connect the can with the shaft so that it will be again rotated in unison with the needle cylinder. The disengagement and reengagement of the clutch members is preferably effected by raising and lowering the can through mechanism operated from the pattern mechanism of the machine.

The means shown for raising and lowering the can to disconnect it from and connect it with the shaft 30 comprises an annular support 50 underlying the bottom of the can and pivotally supported on a yoke 52 at the forward end of a lever 54. The rear end of the lever is engaged by a collar 56 on a vertical rod 58, the upper end of which is arranged to be engaged by a lever 60 which is in turn engaged and actuated by cams 62 on the pattern shaft 64 of the machine. The support 50 is held yieldingly in position by supporting springs 66 and is provided with friction material 68 so that it acts as a brake for arresting the rotation of the can when it is lifted as well as a support for holding it out of engagement with the clutch disk 48.

While it is preferred to employ the specific construction and arrangement of parts shown and described in embodying the invention in the machine of the application above referred to it will be understood that this construction and arrangement is not essential to the broader features of the invention and may be varied or modified as found desirable or best suited to the construction and mode of operation of the ma-

chine to which the invention is to be applied.

What is claimed is:

1. A knitting machine having, in combination, a rotating and reciprocating needle cylinder, a fabric receiver below the cylinder, mechanism underlying and engaging the lower end of the fabric receiver for rotating it in unison with the needle cylinder during rotary knitting, and means for disconnecting the receiver during reciprocatory knitting. 75

2. A knitting machine having, in combination, a rotating and reciprocating needle cylinder, a fabric receiving can having an open upper end which is spaced from the lower end of the needle cylinder and is unobstructed to give free access to the can, mechanism connected with the can below its upper end for rotating it in unison with the cylinder during rotary knitting, and means for interrupting the rotation of the can during reciprocatory knitting. 80

3. A knitting machine having, in combination, a rotating and reciprocating needle cylinder, a fabric receiver below the cylinder, a clutch at the lower end of the receiver through which it is rotated in unison with the needle cylinder during rotary knitting, and mechanism for disengaging the clutch during reciprocatory knitting. 90

4. A knitting machine having, in combination, a rotating and reciprocating needle cylinder, a fabric receiving can below the cylinder, a clutch member on the lower end of the can, a cooperating rotary clutch member on which the can is supported during rotary knitting, and a vertically movable support for lifting the can during reciprocatory knitting. 100

5. A knitting machine having, in combination, a rotating and reciprocating needle cylinder, a vertical shaft below the cylinder, a fabric receiving can mounted on the shaft, a clutch for connecting the lower end of the can with the shaft, and means for disengaging the clutch during reciprocatory knitting. 105

6. A knitting machine having, in combination, a rotating and reciprocating needle cylinder, a vertical shaft below the needle cylinder, a fabric receiving can mounted on the upper end of the shaft, a toothed rib on the lower end of the can, a toothed supporting disk on the shaft, and means for raising the can to disengage the rib from the disk during reciprocatory knitting. 115

7. A knitting machine having, in combination, a needle cylinder, mechanism for rotating and for oscillating the cylinder, a fabric receiver below the cylinder, a rotary support underlying and rotating the receiver, and means for raising the receiver from the support during reciprocatory knitting. 125

MAX C. MILLER.
